CLAIM

I claim the ornamental design for a food guard bowl, as shown and described.

DESCRIPTION

FIG. 1 is a perspective view of a food guard bowl showing my new design with the guard down;
 FIG. 2 is a right-side elevation view thereof;
 FIG. 3 is a left-side elevation view thereof;
 FIG. 4 is a front elevation view thereof;
 FIG. 5 is a back elevation thereof;
 FIG. 6 is a top plan view thereof;
 FIG. 7 is a bottom plan view thereof;
 FIG. 8 is a perspective view thereof, showing the food guard bowl with the guard up;
 FIG. 9 is a right-side elevation view thereof;
 FIG. 10 is a left-side elevation view thereof;
 FIG. 11 is a front elevation view thereof;
 FIG. 12 is a back elevation thereof;
 FIG. 13 is a top plan view thereof; and,
 FIG. 14 is a bottom plan view thereof.
